Patented Feb. 27, 1917.

UNITED STATES PATENT OFFICE.

ROBERT B. TUFTS, OF NORFOLK, VIRGINIA.

REINFORCED CONCRETE STRUCTURE.

1,217,535.

Specification of Letters Patent. Patented Feb. 27, 1917.

Application filed April 28, 1914. Serial No. 834,995.

To all whom it may concern:

Be it known that I, ROBERT B. TUFTS, of Norfolk, in the county of Norfolk and State of Virginia, have invented certain new and useful Improvements in Reinforced Concrete Structures; and I do hereby declare the following to be a full, clear, and exact description of the invention, such as will enable others skilled in the art to which 5 it appertains to make and use the same.

This invention relates to reinforced concrete floors, roofs, reservoir covers and the like,—the object of the invention being to attain to economy of material and cost of 15 constructing the structure; to simplify and make more scientific the calculations of stresses, and to increase the safety of the structure, together with the attainment of various advantages as applied to certain 20 specific conditions.

With this object in view, the invention consists in composing each bay of a floor, roof or reservoir cover of a plurality of groined arch units arranged in two series 25 of intersecting rows, each groined arch unit separated from its neighbor and partly supported by beams crossing each other, which in turn are monolithic with and supported by girders bordering all sides of and separating the bays.

The invention further consists in certain novel features of construction and combinations of parts as hereinafter set forth and pointed out in the claim.

35 In the accompanying drawings; Figure 1 is a plan view of a fragment of a floor, roof or reservoir cover embodying my improvements, said fragment comprising slightly more than one bay; Fig. 2 is a sectional view 40 on the line $x-x$ of Fig. 1; Fig. 3 is an enlarged plan view of one of the groined arch units; Fig. 4 is a sectional view of said unit; Fig. 5 is a sectional view, on a larger scale than that of Fig. 2, illustrating the 45 process of construction, with reinforcing bars in place for the girders and beams; Fig. 6 is a fragmentary sectional view similar to Fig. 5, but with the girders and beams complete and the false work removed; Fig. 50 7 is a sectional view similar to Fig. 2 but showing a modification in the width and depth of the beams and girders.

Preparatory to and in the early stages of 55 the construction of a floor, roof or reservoir cover, I provide a suitable convex molding surface (not shown in the drawing) and

mold independent of and if desirable at a point distant from the structure, a sufficient number of the groined arch units 1, generally rectangular in shape and which may be conceived to be two common arches intersecting each other, the axes of the two arches being substantially at right angles to each other. These units 1 may properly be called groined arches and may be more or less perfect in their molded surfaces, but the important features are that they shall be approximate or perfect rectangles as the bays are approximately or perfectly rectangular in shape, and they shall further be shaped to act as arches by having their center portions of upper surface higher than the plane of the four sides. These units may have reinforcing bars or fabric embedded therein for increasing their strength, without altering the principles involved, but such reinforcement is not necessary to my invention and on the contrary the elimination of the necessity for reinforcement in the units is one of the desirable advantages 70 attained by convexing these units.

These units 1 having been previously designed, dimensioned and molded in sufficient numbers and being sufficiently hardened, they are positioned (see Fig. 5) on beam 85 and girder molds 2 and 3, the sides of the beam or the beam and girder molds supporting on all four sides the unit 1. These sides of the beam and girder molds are less than the desired depth of beams and girders 90 by an amount that will permit the edges of units 1 to be wholly below the tops of the beams and girders, so that the maximum contact will be obtained between beams and girders and the edges of the units 1. 95

As shown by Figs. 5, 6 and 7 the units 1 will project a slight amount into the spaces 4 and 5 which become beams and girders when filled with concrete, so that after the beams and girders shall have been molded 100 and become hard and the molds 2 and 3 removed, the units 1 not only have contact on all four sides with beams or beams and girders, but the latter afford gripping and supporting contact on all four sides. 105

It is clear that if the beams and girders are sufficiently stiff and strong both vertically and horizontally the peripheries of the groined arch units 1 will be held rigidly and these units being convexed upwardly in 110 their center portion and otherwise properly shaped will act as arches in supporting

their loads and will therefore be in compression throughout and will require no reinforcement. Since concrete is capable of withstanding great compressive strains, it requires no argument to show that these units 1 may be of comparatively small thicknesses and therefore the groined arch units lend themselves to economical design as concerns material used.

10 The beams and girders will be proportioned according to well known engineering theories to withstand bending and breaking tendencies arising from the loads to be sustained, a due consideration of which will 15 call for the beams being comparatively small with relation to the girders.

It will be observed that each bay is made with a plurality of the units 1 symmetrically arranged about the center of the bay, the 20 dimensions of the units 1, the beams 6 and 7 and the girders 8 and 9, being harmonized so that each will be of proper strength to carry the loads coming to each.

It is also clear that this design is best 25 adapted to truly square bays but can be applied to bays of any shapes met with in construction. When the bays are perfect squares, the units 1 are logically perfect squares and the dimensions of all beams are 30 the same and of all girders are the same and the arrangement of units 1 and of beams and girders are symmetrical. Variations from perfect squares in the bays make corresponding variations in the units.

35 In the drawings, nine groined arch units to each bay, are shown, and while this will often be the most suitable number, it is clear that more or less than this number may be employed.

40 Without affecting the principles brought out, the beams and girders may be very wide and comparatively shallow as shown in Fig. 7 or they may be deep and narrow.

In order to attain to greatest economy in 45 beam and girder design, all beams and girders will be reinforced by having bars near their under surfaces at and near midway between supports and these bars bent up and near the upper parts of beams at and near 50 supports sufficient lap being given the bars in girders over columns 11 (located at the corners of the bays) to insure them acting as beams continuous over supports and the bars at the ends of beams likewise having 55 sufficient embedment to insure the beams acting as rigidly fixed at their supports.

It is clear that superloads on the groined arch units 1 by virtue of their arch action will exert horizontal thrusts on the 60 beam or beams and girders performing the functions of abutments. It is also clear that for all beams and girders other than those

bordering the extreme outsides of the structure, the thrust from one arch will be counteracted by the equal and opposite 65 thrust from its neighbor and therefore little or no attention need be taken of the side-wise thrust on the beams and girders except for the outside girders. The outside girders have unbalance thrusts, from the inside 70 only, but these girders for other considerations will require to be comparatively wide and stiff, hence will require little or no additional sidewise stiffening to resist these 75 thrusts.

As applied to floors, the groined arches will give rise to irregular surfaces that will require filling material to produce level surfaces, but for reservoir or roof constructions 80 it is a common practice to place thereon two or three feet of earth filling in which case the irregular surface produced by the groined arches is not objectionable.

By studying the compressive stresses in the groined arches with due regard to the 85 compressive strength of concrete it will be observed that theoretic requirements will generally call for surprisingly thin groined arches and that it will be practically impossible to cause one of these groined arches to 90 fail from a superposed load, providing the horizontal thrusts are resisted; all of which directs attention principally to strength of beams and girders, which latter can be logically assumed to be uniformly loaded and 95 fixed at or continuous over supports, and therefore the analysis of stresses will be simplified and the conditions are favorable to economy of design.

Having fully described my invention what 100 I claim as new and desire to secure by Letters-Patent, is:—

A concrete structure comprising a plurality of concrete girders arranged in rectangular formation, transverse concrete beams 105 dividing the space bounded by said girders into smaller spaces, said girders and beams forming a monolithic structure, and comparatively thin precast groined arch panel units, each having less thickness than that of the girders and beams, said groined arch panel units closing said smaller spaces and having their edge portions embedded in the 110 walls of the monolithic structure intermediate the upper and lower faces of the same, and supported by said monolithic structure.

115 In testimony whereof, I have signed this specification in the presence of two subscribing witnesses.

ROBERT B. TUFTS.
